Filed June 26, 1972, Ser. No. 266,489

Term of patent 14 years

Int. Cl. D8—99

U.S. Cl. D8—220

FIG. 2

FIG. 1

FIG. 3

FIG. 4

FIG. 1 is a face view of a reversible feed loader drive pulley embodying my new design, the hidden opposite face being the same as shown in FIG. 1.

FIG. 2 is a peripheral view of the reversible feed loader drive pulley shown in FIG. 1.

FIG. 3 is a fragmentary section taken at 3—3 in the periphery of the reversible feed loader drive pulley shown in FIG. 2.

FIG. 4 is a fragmentary section taken at 4—4 in the periphery of the reversible feed loader drive pulley shown in FIG. 2.

It is understood that the design shown in FIG. 2 is continued on the hidden side of FIG. 2; and that the design illustrated in FIG. 3 and FIG. 4 is repeated in corresponding portions about the periphery of the reversible feed loader drive pulley in accordance with my design.

I claim:

The ornamental design for reversible feed loader drive pulley, as shown and described.
